UNITED STATES PATENT OFFICE.

LESTER A. WERNER, OF ATLANTIC HIGHLANDS, NEW JERSEY, ASSIGNOR OF ONE-HALF TO ALBERT E. HARTCORN, OF NEW YORK, N. Y.

INTERNAL-COMBUSTION ENGINE.

1,189,324.

Specification of Letters Patent.

Patented July 4, 1916.

Application filed April 29, 1915. Serial No. 24,720.

To all whom it may concern:

Be it known that I, LESTER A. WERNER, a citizen of the United States, and resident of Atlantic Highlands, in the county of Monmouth and State of New Jersey, have invented certain new and useful Improvements in Internal-Combustion Engines, of which the following is a full, clear, and exact specification.

10 My invention relates to internal combustion engines, and consists of the herein shown and described improvements in the construction of such engines, devised with the object in view to combine, in one engine, the advantages of the two and four cycle operation, and to eliminate the disadvantages of both. In a two cycle internal combustion engine, an impulse is given to the piston, by the ignition of the explosive mixture, at the beginning of each down-stroke thereof. This operation, however, interferes with the expelling of the gases, produced by the ignition of the explosive mixture, which results in the impairment of the efficiency of 20 the engine, the unexpelled products of the combustion mingling with the fresh mixture, thus becoming more and more detrimental to the proper operation of the engine at higher speeds. This defect is avoided 25 in the operation of a four cycle internal combustion engine, but in those engines the ignition of the explosive mixture takes place only at every second downward-stroke of the piston, by reason of which there is 30 a great diminution of kinetic energy during the period, intervening between the successive impulses, and by the propelling of the piston, twice on its upward-stroke, first for the expulsion of the burnt gases, and 35 second for the compression of the fresh charge, besides propelling it in its downward stroke when the charge of the explosive mixture is drawn in. This loss of kinetic energy is avoided and the stated object of my invention attained by so dividing 40 the cylinder of a four cycle engine into sections, so that separate combustion chambers are formed therein, and by providing separate valve chambers, and separate intake and 45 exhaust valves, for each combustion chamber, and separate gears for each valve. In an engine of this construction, the piston receives an impulse by the ignition of the explosive charge, on each downward stroke, 50 and yet the engine is free from the defect

of a two cycle engine, as the gases, produced by the ignition of the explosive mixture, are always fully expelled from each division of the combustion chamber before a fresh charge of the explosive mixture is 60 drawn in again.

An engine, constructed according to the stated principles of my invention, is illustrated in the accompanying drawings, wherein—

65 Figure 1 is a vertical section through the engine on line 1—1, indicated in Fig. 2, some parts being shown in elevation; Fig. 2 is an elevation at right angle to Fig. 1, part of the casing being broken away to show the 70 parts of the engine within the casing; Fig. 3 is an enlarged horizontal section on line 3—3, indicated in Fig. 1; Fig. 4 is an enlarged vertical section through the upper part of the engine, on line 4—4, indicated 75 in Fig. 1; Fig. 5 is an enlarged horizontal section on line 5—5, indicated in Fig. 1, looking downward; Fig. 6 is an enlarged fragmentary, vertical sectional view, corresponding to a portion of the left-hand side 80 of Fig. 1, with some portions broken away, to show the construction of the packing for the piston partition; Fig. 7 is an inverted plan view of the partition casing, illustrating also the stuffing box in the position it 85 occupies when set in the inner wall of the cylinder head with the follower removed; and Fig. 8 is a plan view of the follower.

90 The engine comprises the usual casing, the design whereof is somewhat modified to provide additional valve chambers, and which includes also an extension 8 for housing the partition 7, dividing the space in the cylinder 50 above the piston into two sections 10 and 11. The partition 7, is made 95 integral with, or connected to the piston 53, and passes through an opening in the head of the cylinder, made for this purpose, into the extension 8 of the cylinder casing. The aperture in the inner wall of the head of the 100 cylinder is made sufficiently wide to permit the insertion therein of the stuffing box 51, by which a gas-tight fitting of the partition 7 is effected to prevent the escape of the compressed explosive mixture, or of the 105 combustion gases, from the cylinder. The length of the partition 7 corresponds to the stroke of the piston, so that at its lowest position, at the end of its downward stroke, the upper end of the partition 7 stands 110

slightly above the stuffing box. The width of the partition 7, is co-extensive with the diameter of the bore of the cylinder. To secure a gas-tight joint between the partition 5 7 and the partitions 16, separating the valve chambers, the edges of the partition 7 are bifurcated and suitable packing set therein. This packing, as shown in the drawings, is made up of the strips 13 of compressible 10 material mounted on metallic bars 44, and springs 43, set in the bores as shown in Figs. 5 and 6, are provided to press the packing strips 13 against the partitions 16. The extension of the casing communicates through 15 passages 22 with the water jacket 21 of the cylinder, to enable the cooling water to circulate therethrough, whereby the partition 7 is cooled.

The formation of the valve chambers, and 20 the location of the valves therein, are illustrated in Fig. 3. Partitions 16 between the valve chambers are preferably cast as integral parts of the cylinder casing. Each valve chamber connects with its respective 25 division of the combustion chamber through an open port, and through the valve, seated therein, with the intake, or exhaust port of the engine. The intake and exhaust valves 33 and 34, and 35 and 36 respectively, are 30 of the usual construction, employed in engines of this kind, and are operated by cams adjustably fixed on cam-shafts 28 and 45, driven by the gears, illustrated in Figs. 1 and 2, from the crank-shaft. Separate 35 means for igniting the explosive charge in each division of the combustion chamber are provided. Spark plugs 37 are preferably used for this purpose in connection with a suitable ignition device. By thus dividing 40 the cylinder by a partition connected to the piston, to form two separate combustion chambers, and providing separate ports, and valves, for each division, an explosion takes place at the completing of each upward 45 stroke of the piston, an impulse being thus imparted to the piston at the start of its downward stroke.

For seating the stuffing box, the inner wall of the cylinder head is extended to produce 50 the flange 17, and a flange 41 is made on the stuffing box, to extend over the edge of the flange 17, and a suitable recess for the reception of the compressible packing 42 is made in the flanges 17 and 41, whereby a 55 gas-tight joint between the flange of the stuffing box and the flange of the cylinder head is produced. The packing 52 is formed to correspond to the cross-section outline of the partition 7, and so is the follower 18, 60 fitted into the recess of the stuffing box. This follower is secured therein, and the packing 52 compressed, by screw-bolts 19, which serve also to secure the stuffing box in its seat in the opening of the inner wall 65 of the cylinder head.

The cam-shafts 28 and 45 are driven by the gear-wheels 23, mounted on the crank-shaft 24, and meshing with the intermediate gear-wheels 25, rotatably mounted on studs 26. The intermediate gear-wheels 25 mesh with 70 the gear-wheels 27 mounted on the cam-shafts 28 and 45. The driving gears are proportioned to rotate the cam-shafts 28 and 45 at one-half of the speed of the crank-shaft 24. Cams 29 and 31, mounted on cam-shaft 28, actuate the intake valves 33 and 35, and cams 30 and 32, mounted on cam-shaft 45, actuate the exhaust valves. The cycle 75 of the operations of the engine is as follows: Beginning with the piston 53 in its 80 uppermost position, and assuming that one of the divisions (10) of the combustion chamber is then filled with a compressed charge of the explosive mixture, the intake valve 33 and the exhaust valve 34 closed;— 85 the other division (11) of the combustion chamber is empty, the combustion gases having been expelled therefrom by the upward stroke of the piston; the exhaust valve 36 has just been closed and the intake valve 35 90 just begins to open,—the compressed charge in the division 10 is now exploded. The piston is then started on its downward stroke. The intake valve 35 is now fully open and a fresh charge of the explosive 95 mixture is drawn in, into the division 11 of the combustion chamber. At the completion of the downward stroke of the piston, the other division (11) of the combustion chamber is filled with the fresh charge of 100 explosive mixture, and a compression thereof takes place during the upward stroke of the piston, while at the same time, the exhaust valve 34 is opened and the combustion gases, produced by the previous ignition of 105 the explosive mixture in the first division (10) are being simultaneously expelled. When the piston reaches the end of its upward stroke, the explosive charge in division 11 is compressed, and ready to be ignited. 110 On its being ignited, the piston receives a downward impulse by the expansion of the combustion gases, the valve 33 is opened, the exhaust valve 34 closed, and a fresh charge 115 of explosive mixture is drawn into the division 10 of the combustion chamber, the same operations being repeated. In these alternating operations, the piston of the engine receives an impulse at the termination of each upward stroke as in a two cycle engine, but the disadvantages of a two cycle operation are avoided, in that the combustion gases are always fully expelled from each of the combustion chambers, before a 120 fresh charge of this explosive mixture is drawn in. There is also a complete compression of the explosive charge effected in each division of the combustion chamber during the entire upward stroke of the piston. 125 130

I claim as my invention:

1. An internal combustion engine, comprising a casing, a cylinder in the casing, a piston in the cylinder, a partition dividing the combustion chamber, connected with the piston; separate valve chambers for each division of the combustion chamber, intake and exhaust valves set therein, valve operating gears for actuating the valves in each division independently of the other, and means for igniting the explosive charge in each division of the combustion chamber; substantially as herein shown and described.
2. An internal combustion engine, comprising a casing, a cylinder, and valve chambers, communicating therewith, in the casing; a piston in the cylinder, a movable partition dividing the combustion chamber, an intake and an exhaust valve for each division of the combustion chamber, partitions in the casing between the intake and exhaust valves of each division of the combustion chamber, valve operating gears for actuating the valves in each division independently of the other, and means for igniting the explosive charge in each division of the combustion chamber; substantially as herein shown and described.
3. An internal combustion engine, comprising a casing, a cylinder in the casing; a piston in the cylinder, a partition, dividing the combustion chamber of the cylinder, secured to the piston, separate valve chambers for each division of the combustion chamber and communicating therewith; intake and exhaust valves set therein; valve operating gears for actuating the intake and the exhaust valves in each division independ-

ently of the other, and means for igniting the explosive charge in each division of the combustion chamber; substantially as herein shown and described.

4. A four cycle internal combustion engine, comprising a casing, a cylinder, a movable partition fitted into the cylinder and dividing the combustion chamber into sections; separate valve chambers and a set of intake and exhaust valves for each section of the combustion chambers; gears for actuating the intake and the exhaust valves in each section independently, and means for igniting the explosive charge in each section of the combustion chamber; substantially as herein shown and described.

5. A four cycle internal combustion engine, comprising a casing, a cylinder and valve chambers communicating therewith, in the casing; a piston in the cylinder; a partition, secured to the piston, and dividing the combustion chamber into sections; partitions in the valve chambers, dividing each into the same number of sections as that into which the combustion chamber is divided; an intake and an exhaust valve for each section of the combustion chamber; means for igniting the explosive charge in each section of the combustion chamber; and gears for actuating the intake and the exhaust valve in each section of the combustion chamber independently; substantially as herein shown and described.
